[57] CLAIM

The ornamental design for a meter box padlock, as shown and described.

DESCRIPTION

FIG. 1 is a side elevational view of a meter box padlock showing my new design;

FIG. 2 is a front elevational view of the padlock;

FIG. 3 is a rear elevational view of the padlock;

FIG. 4 is a top plan view of the padlock;

FIG. 5 is a bottom plan view of the padlock;

FIG. 6 is a partially sectional and partially top plan view taken approximately along the line 6—6 of FIG. 1; FIG. 7 is a side elevational view of the removable shackle of the padlock;

FIG. 8 is a bottom plan view of the shackle of the padlock;

FIG. 9 is a rear elevational view of the shackle of the padlock; and

FIG. 10 is a rear perspective view of the case of the padlock.

The unillustrated side elevational view of the shackle of the padlock is a mirror image of FIG. 7.

The characteristic features of my design reside in the shackle and its relationship to the case of the padlock.
